UNITED STATES PATENT OFFICE.

CHARLES DICKENSON, OF PORTLAND, OREGON.

AUTOMATIC MARINE GOVERNOR.

SPECIFICATION forming part of Letters Patent No. 337,817, dated March 16, 1886.

Application filed July 8, 1885. Serial No. 170,928. (No model.)

To all whom it may concern:

Be it known that I, CHARLES DICKENSON, a citizen of the United States, residing at Portland, in the county of Multnomah and State of Oregon, have invented certain new and useful Improvements in Automatic Marine Governors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to marine governors for steamships, and the object is to provide an automatic device for regulating the speed of the engines; and to this end the novelty consists in a float located near the screw 20 on the outside of the vessel, so arranged as to be operated by the water to raise and lower it, and provided with means for transmitting said motion directly and instantly to the throttle or an independent governor valve, where- 25 by the supply of steam to the engines will be increased or diminished as the waves raise or lower the float and in proportion to the distance which the float rises and falls, as will be hereinafter more fully described.

30 In the accompanying drawings the same letters of reference indicate the same parts of the invention.

Figure 1 is a longitudinal sectional view of a steamship with my improved governor in 35 position, and Fig. 2 a detail of the valve-gear.

A is a guide-rod, preferably made of pipe, and screwed into the hinged shoe B, while its upper end passes through a guide-bracket, C.

D is a hollow metal float, which may be 40 fashioned after any suitable ornamental design. This float has a free vertical movement the entire length of the guide-rod A, on which it slides, and the guide-rod may be round, as shown, or angular, to prevent the float revolving about the rod. Where the round guide- 45 rod is used, the tail of the figure float forms a rudder, d, and when the vessel is in motion it keeps the float in its proper position.

In case it is necessary to apply the governor 50 to a vessel while afloat, it can be done without docking her by securing the lower end of the

guide-rod in position by stays or braces in any convenient manner.

From the float D a chain, E, runs over anti-frictional pulleys to a pulley, e, thence 55 around a block, F, secured to the governor lever G, and back again to the hook e' on the pulley e. It will thus be seen that the lever G is raised as the float D falls, and, reversely, the lever lowers as the float rises. The lever 60 G is attached to a plug-cock or governor-valve, H, so arranged that when the lever is up to its highest point the supply of steam is entirely shut off, and when the lever is at its lowest point the said valve is open to its full 65 limit. Therefore, as the float falls it raises the lever and cuts off the steam proportionate to the distance which the float moves, and as the float rises the lever falls and admits steam likewise in the same proportion, and as the 70 float is set or adjusted to correspond to the draft of the ship and position of the screw it follows that as a wave leaves a portion of the screw bare the float falls to that exact point, and consequently an amount of steam is cut off 75 proportionate to the surface of screw exposed above the water, and should a wave leave the screw entirely bare the lever G may be so adjusted as to not cut the steam off entirely, but 80 keep the engines revolving, to prevent an undue strain on the screw when it again enters the water and the full head of steam is turned on. The pulley e is adjustably secured to the lever G by a thumb-screw, c, by means of 85 which it may be moved in or out on the lever to compensate for the water or load line of the vessel, so that the float may be correspondingly set whether the vessel is light or loaded.

I is a weight on the lever G, adjustably secured thereon by a set-screw, i, to counter-balance the weight of the float, which of course may be appropriately weighted to overcome the friction of the chain, pulleys, and valve, and thus secure an instant movement of the valve for each variation of the float.

When the vessel is in the dock or in calm waters and the service of the governor not needed, the engineer by means of the chain may raise the float up under the stern, and whether it is in use or not it in no way interferes with the use of the regular throttle-valve, K.

A very important feature of my improved governor is, that it is operated entirely and automatically by the action of the water irrespective of the position of the vessel, as in a chop-sea the vessel may maintain a comparatively level position, while the waves will rise and fall so as to expose the screw, and consequently a governor operated by the motion of the vessel would not be effective or reliable; 5 but in my case the float responds to every variation of the water-level, irrespective of the motion or position of the ship—a result that must be attained to produce a perfect governor for marine use.

10 Having thus fully described my invention, what I claim as new and useful, and desire to secure by Letters Patent of the United States, 15 is—

1. In a marine governor, a float located in the rear of the rudder outside of the vessel, so as to be operated by the water, and means for transmitting said motion to the governor-valve, substantially as set forth.

2. The combination, with the float D, having rudder d, of the guide-rod A, chain E, 20 lever G, and valve H, as and for the purpose set forth.

In testimony whereof I affix my signature in presence of two witnesses.

CHARLES DICKENSON.
